UNITED STATES PATENT OFFICE.

JOHN ANDREW STIH, OF LA SALLE, ILLINOIS.

DESIGN FOR A GARTER.

55,826.

Specification for Design.

Patented July 13, 1920.

Application filed February 24, 1920. Serial No. 360,993. Term of patent 7 years.

To all whom it may concern:

Be it known that I, JOHN ANDREW STIH, a citizen of the United States, residing at La Salle, in the county of La Salle and State of Illinois, have invented a new, original, and ornamental Design for Garters, of which the following is a specification, reference being had to the accompanying drawing, forming part thereof.

The figure is a view of a garter in side elevation, showing my new design.

I claim:

The ornamental design for a garter, as shown.

JOHN ANDREW STIH.

Witnesses:

ANTON STIH,
JOHN FITZGERALD.
